UNITED STATES PATENT OFFICE

ROBERT LUNGSTRAS, OF ST. LOUIS, MISSOURI

METHOD OF MANUFACTURING RELATIVELY NONINFLAMMABLE CLEANING FLUIDS

No Drawing.

Application filed June 23, 1930. Serial No. 463,362.

The object of my invention is a method of manufacturing a relatively non-inflammable dry cleaning fluid; one that can be made cheaply and easily and one which has all the dry cleaning power of gasoline or carbon tetrachloride. By my method gasoline, crude oil, tar and other substances of like quality may be treated so as to produce a dry cleaning liquid, which is relatively non-inflammable. In other words my method, when applied to gasoline, raises the flash point to such an extent that as a practical matter the gasoline becomes non-inflammable.

With these and other objects in view my invention has relation to certain methods and steps in the operations, as will be hereinafter more fully described and pointed out in the claims. The preferred material to be treated is gasoline. This is placed in a container and to it is added nitrogen in liquid form. The preferable proportion is five parts by volume of gasoline and one part by volume liquid nitrogen. A sufficient quantity is placed in the container to half fill it. The container is then closed and heated to a temperature of 2500 degrees Fahrenheit, at which temperature it is maintained for a period of approximately one half hour. The container is cooled to atmospheric temperature, opened, and the finished product, which is a liquid, remains. By the term "gasoline", applicant means all of its grades, as well as naphtha.

What I claim and mean to secure by Letters Patent is:

- 35 1. A method of reducing the inflammability of solvent, which consists in impregnating the gasoline with nitrogen, at a temperature of approximately 2500 degrees Fahrenheit.
- 40 2. A method of reducing the inflammability of gasoline, which consists in mixing the solvent with liquid nitrogen, at a temperature of approximately 2500 degrees Fahrenheit.
- 45 3. A method of reducing the inflammability of gasoline, which consists in mixing the solvent with nitrogen under pressure, at a temperature of approximately 2500 degrees Fahrenheit.
- 50 4. A method of manufacture for the purposes described, which consists in mixing

gasoline with liquid nitrogen under pressure, at a temperature of approximately 2500 degrees Fahrenheit.

5. A method of treating gasoline by mixing it with liquid nitrogen and heating the mixture, at a temperature of approximately 2500 degrees Fahrenheit.

6. A method of treating gasoline by mixing it with liquid nitrogen in a closed vessel and subjecting the vessel to heat, at a temperature of approximately 2500 degrees Fahrenheit.

7. A method of treating gasoline, which consists in mixing it with nitrogen in a closed vessel and subjecting the vessel to heat, at a temperature of approximately 2500 degrees Fahrenheit.

8. A method of manufacture for the purposes described, which consists in mixing five parts of gasoline and one part liquid nitrogen by volume in a vessel of a larger volume than that displaced by the liquid, sealing the vessel and subjecting it to a temperature, of approximately 2500 degrees Fahrenheit.

9. A method of manufacture for the purposes described, which consists in mixing five parts of gasoline and one part liquid nitrogen by volume in a vessel twice as large as the volume displaced by the liquids, sealing the vessel and subjecting it to a temperature of 2500 degrees Fahrenheit for one-half hour.

10. A method of manufacture for the purposes described, which consists in mixing five parts of gasoline and one part liquid nitrogen by volume in a vessel having a volume equal to twice that displaced by the liquids, sealing the vessel and subjecting it to a temperature of 2500 degrees Fahrenheit for approximately one-half hour.

In testimony whereof I affix my signature,

ROBERT LUNGSTRAS.
